UNITED STATES PATENT OFFICE.

ARTHUR GRANDJEAN, OF NATIONAL CITY, CALIFORNIA.

BEDCLOTHES-CLAMP.

SPECIFICATION forming part of Letters Patent No. 770,003, dated September 13, 1904.

Application filed October 3, 1903. Serial No. 175,664. (No model.)

To all whom it may concern:

Be it known that I, ARTHUR GRANDJEAN, M. D., a citizen of the United States, residing at National City, in the county of San Diego and State of California, have invented new and useful Improvements in Bedclothes-Clamps, of which the following is a specification.

My invention relates to improvements in bedclothes-clamps; and the object is to simplify and improve the construction of devices designed for clamping and holding the bedclothes to prevent them from working up beyond the foot of the bed or mattress.

The invention embodies a clamp comprising a fixed or stationary jaw, a movable jaw, and clamping means to close the movable jaw, all as will be hereinafter specified, and the asserted novelty particularly pointed out and distinctly claimed.

15 I have fully and clearly illustrated the improvements in the annexed drawings, to be taken as a part of this specification.

Reference being had to the drawings, Figure 1 is a perspective view of a bedstead and bed arranged thereon and my improved bedclothes-clamps applied to the covers. Fig. 2 is a view in elevation of the clamps as applied to the foot-rail of the bedstead. Fig. 3 is a detail side view of one of the clamps as applied to the vertical flange of the bed-rail. Fig. 4 is a vertical central section through the clamp shown in Fig. 3, with the bedclothes clamped between the jaws. Fig. 5 is a vertical central section through the clamp, showing the jaw-screw as having its inner end formed with a hook to engage over the horizontal flange of the bed-rail and the jaws as opened. Fig. 6 is a vertical central section wherein the fixed jaw of the clamp is riveted 30 to the bed-rail. Fig. 7 is a detail side view wherein the clamping-bars are shown as made of round bars. Fig. 8 is a view in elevation, showing the clamps of Fig. 7 secured and arranged on the bed-rail. Fig. 9 is a detail view of the eccentric clamping-lever.

In the drawings similar parts or elements appearing in the different illustrations are designated by the same reference-notations.

Referring to the drawings, A designates a 50 bedstead of the usual construction, on which

is shown the usual mattress-bed with covering arranged thereon, and to the foot-rail 1 of the bedstead are secured my improved bedclothes-clamps. The bed shown is the usual style or construction of iron bedsteads wherein the 55 foot-rail is made of a bar of angle-iron; but it is apparent that the clamps may be utilized with very slight change in connection with any shaped foot-rail—round, square, or angular—by simply making the lower portion 60 of the fixed jaw to substantially conform to the contour of the rail. In the use of my improved clamps any certain number may be used. One of them in instances of narrow single beds may serve the purpose, and the 65 number being increased to suit beds of greater widths just as the convenience or requirements may demand.

The bedclothes-clamps comprise or are made up of a fixed jaw 2, having its lower end 70 formed into a hook 3 to engage under and take in the vertical depending flange of the foot-rail, substantially as shown, and a movable jaw 4, which at its lower end portion is provided with an opening through which a screw 75 5 is somewhat loosely projected, so as to give the jaw sufficient play or movement to open wide enough to permit the bedclothes to be inserted between the jaws. The screw 5 passes through the stem of the fixed jaw and 80 is provided with an adjusting-nut 6, whereby the relation of the movable jaw to its companion may be regulated. The direction of the screw may be changed, as shown, in some instances, the head resting on the foot-rail and 85 in others the nut. The vertical jaw-pieces have secured to them suitable horizontal parallel clamping-bars 7, which bars connect stems or jaw-pieces of the clamps and maintain them in fixed relation to each other. The 90 clamping-bars 7 are in parallel alinement and are of such length as may be required and in contour in cross-section may be round, as seen in Fig. 7, half-round or flat, as shown in the other figures. To each clamp is secured 95 a band or bracket 8, embracing the clamps on three sides, the side pieces of which bracket are extended to form ears 9, between which is journaled an eccentric 10, provided with a handle 11 to operate it. It will be readily 100

seen that the position of the eccentric will correspondingly actuate the movable jaw to clamp or release the bedclothes which may be placed between the clamping-bars.

5 In Fig. 5 of the drawings the screw 5 is shown as extended over the foot-rail and bent to hook under it, as at 12, which form becomes useful in case the bedclothes are many or heavy, and in Fig. 6 the stem of the fixed 10 jaw is shown as riveted to the foot-rail, which is the form of connection preferable in stock where the device goes with the bed. Where the devices are to be utilized on beds in use and originally without them, the stems of the 15 fixed jaws are arranged on the foot-rail, as seen in the drawings, and then the eccentrics are turned with the handle downward, then the bedclothes are drawn and arranged between the bars, which constitute the clamping 20 members, and when adjusted to suit the eccentrics are turned until the handles stand vertical and the bedclothes are held clamped.

The device, it will be seen, holds the bedclothes down and prevents them from being 25 drawn up at the foot and also conveniently holds the bedclothes while airing them, since they may be thrown over the foot-frame for that purpose, and in making up the bed the covers can be readily and smoothly spread 30 and the clamping means in both instances remain engaged and undisturbed.

Having thus fully described the invention, what is claimed as new is—

1. The combination with the foot-rail of a

bedstead, of bedclothes-clamps each consisting 35 of a fixed jaw having its lower end formed with a hook to engage the rail, a movable jaw, an adjusting-screw device loosely passed through the lower portions of both jaws, an eccentric 40 coöperating with the pairs of jaws, and opposed clamping cross-bars secured to the upper ends of both the fixed and movable jaws, the lower ends of the movable jaws being unconnected with relation to the fixed jaws and held in assembled relation to the fixed jaws 45 solely by the loose adjusting-screws.

2. A bedclothes-clamp adapted to be held applied to the foot-rail of a bedstead and consisting of fixed jaws arranged at regular intervals and having lower extremities to engage the foot-rail of a bedstead, movable jaws 50 coöperating with the fixed jaws, nutted-screw devices extending through the fixed jaws and loosely passing through the lower extremities of the movable jaws and forming the sole 55 means for adjusting and holding said movable jaws in operative relation to the fixed jaws, and bands or brackets surrounding both jaws and secured to the fixed jaws and having eccentrics journaled in the outer portions thereof 60 to engage the outer sides of the movable jaws at points above the screw devices.

In testimony whereof I affix my signature in presence of two witnesses.

ARTHUR GRANDJEAN.
